UNITED STATES PATENT OFFICE.

BEN McCULLOCH GOLDSMITH, OF PHILADELPHIA, PENNSYLVANIA.

DESIGN FOR A BRUSH.

Application filed April 19, 1924. Serial No. 9,321. Term of patent 3½ years.

To all whom it may concern:

Be it known that I, BEN McCULLOCH GOLDSMITH, a citizen of the United States, residing at Philadelphia, in the county of Philadelphia and State of Pennsylvania, have invented a new, original, and ornamental Design for a Brush, as shown in the accompanying drawing and described in the following specification:

The figure is a perspective view of a brush showing my new design.

I claim:

The ornamental design for a brush as shown.

BEN McCULLOCH GOLDSMITH.
